OF NEW YORK, N. Y., A CORPORATION OF NEW YORK.

PAPER-FEEDING-MACHINE ATTACHMENT.

No. 907,610.

Specification of Letters Patent.

Patented Dec. 22, 1908.

Application filed September 4, 1908. Serial No. 451,692.

To all whom it may concern:

Be it known that I, JOSEPH KLEIDMANN, a subject of the Czar of Russia, and resident of Coney Island, in the city of New York, in the 5 county of Kings and State of New York, have invented certain new and useful Improvements in Paper-Feeding-Machine Attachments, of which the following is a specification.

10 The present invention relates to improvements in that class of machines which is designed to feed successively one sheet of paper at a time from a pile to a printing press, paper folding or ruling machine, or other machines designed to operate upon paper.

More particularly, the invention relates to that class of feeding machines which carries a stack of sheets of paper or the like upon a substantially horizontal table, and from 20 which the sheets are fed by the feeding mechanism unto the feed table.

In order to maintain and hold the other sheets of a pile in fixed and proper positions as the top sheet is being separated therefrom, 25 holders are provided usually, which assure to some extent the separation of but a single sheet of paper from the pile by resting upon the sheets under the top sheet as the top sheet is being removed. Such holders consisted, heretofore, usually of a single contact block, and it will be easily seen that, when the sheets of paper are held only at a single point, the same may be easily brought out of their proper positions by the sheet advancing means; for instance, the advancing means 30 may, although not carrying the same in the direction of their own travel, force the sheets sideward. On the other hand, since the rear edges of the sheets of paper do not coincide as the same are combed, the contact block, heretofore in use, will from time to 40 time allow two sheets to be fed unto the feeding table if not adjusted with particular accuracy.

45 It is now the object of the present invention to provide means, whereby the aforesaid defects of the feeding machines are obviated.

To attain this end, the device consists of a plurality of fingers, engaging the stack of 50 paper but caused to be disengaged with the same immediately before the top sheet is being removed; as now the top sheet is being advanced, the fingers engage in succession

the remaining sheets and always at the smallest possible distance beyond the top sheet, 55 whereby, first, the sheets under that top sheet are prevented in their forward movement, and, second, their proper position is assured.

Other objects of the invention will be apparent from a reading of the specification and an examination of the drawings, forming part of the present application for Letters Patent.

The invention is illustrated in the accompanying drawings, in which— 65

Figure 1 is a side elevation of a paper feeding machine having the attachment, forming the subject matter of the present application for Letters Patent, and Fig. 2 is a side elevation on line 2—2 of Fig. 1, on an enlarged 70 scale.

It will be observed that in Fig. 1 of the drawings only those parts of the feeding machine are shown which are necessary to understand the operation of the improved 75 paper feeding device, which can obviously be attached to a paper feeding machine of any suitable construction, whereby the paper is being fed from a pile to a machine designed to operate upon paper.

In the drawings, 3 indicates one of a pair of the side parts of the frame of the feeding machine, and 4 one of a pair of the uprights, between which and the transverse vertical wall 5 of the frame of the machine is arranged 85 in any suitable manner a vertically movable table (not shown in the drawings), carrying the stack of paper indicated at 6. The transverse vertical wall 5 is provided at its upper end with a forwardly bent lip 7, unto which 90 the sheets are fed by a feeding means 8, actuated by the main shaft 9 of the apparatus, which main shaft is journaled in the side frame 3 and operated by any suitable source of power, for instance, by the intermediary of a chain 10, meshing with a sprocket wheel 11, mounted upon the main shaft 9. The mechanism for transmitting motion from the main shaft 9 to the feeding roller 8 is immaterial and is not described. 95

The sheets are fed from the forwardly bent lip 7 within reach of transporting rollers 12 and 13, and thus unto the feed band 14, which bring the same, in a well known manner, unto the cylinder of the press or to any 105 other suitable apparatus or machine. The

apparatus thus far described does not differ in any essential way from the feeding machines heretofore in use.

The paper retaining or holding device, forming the subject matter of the present application for Letters Patent, is adjustably mounted on a bar 15, arranged parallel to the plane of the top sheet of the pile of paper and at right angles to the main shaft 9 of the apparatus. This bar is mounted in the brackets 16 and 17, attached to the side frame 3 and the upright 4, respectively, and carries the frame 18 of the sheet retaining device, which frame is provided with upwardly extending extensions 19 and 20, which engage the shaft 21, arranged parallel with the bar 15 and at right angles to the shaft 9. The shaft 21 is rotatably mounted in bearings 22 and 23, carried by the frame 3 and the upright 4, respectively, and is provided at its inner end with a bevel gear 24, in mesh with a similar gear 25, mounted upon the main shaft 9. The purpose of this arrangement will be hereinafter more fully described.

The frame of the paper retaining device is provided with a hole 26, fitting the stationary bar 15 and allowing of a sliding movement of the frame relative to the bar, when it becomes necessary to adjust the position of the frame upon said bar. A set screw 27 serves to secure the frame upon the shaft in the desired adjusted position. The frame 18 is furthermore provided with a slot 28, at right angles to the plane of the paper, covered by an upper plate 29 and a lower plate 30, suitably attached to said frame and provided with holes 31 and 32, respectively, which holes are engaged by the holding or retaining fingers 33. The fingers are slidably arranged in the plates 29 and 30, between which are arranged springs 34, each encircling one finger and bearing against the plate 29 and the lower enlarged end 35 of the fingers, tending to keep thus said fingers in their lower positions. The lower end of the fingers may be provided with frictional shoes 36, made of resilient material, such as rubber. The upper ends of the fingers are provided with flanges 37, limiting the downward movement of the fingers, which are pivotally connected with two-armed levers 38, carried by a spindle 39, arranged on the frame 18 of the retaining device. The free ends of the two-armed levers 38 carry rollers 40, in engagement with cams 41, mounted upon the motion transmitting shaft 21.

As shown in the drawings, four fingers 33 are mounted on the frame 18 and, therefore, four cams 41 must be provided. These cams are arranged on a sleeve 42, which is secured by means of a key 43 to the shaft 21. As mentioned hereinbefore, the fingers are lifted simultaneously, but are brought in contact with the paper sheets successively; the cams 41 are, therefore, as shown in the

drawings provided with acting faces of different lengths.

The rear edge of the frame 18 is provided with a finger 44, contacting with the rear edges of the sheets of paper and determining thereby the proper position of the fingers 33 upon the machine.

The operation of the device is as follows: The main shaft 9 of the apparatus operates the feeding means 8 and also the retaining means or fingers 33 in unison motion. More particularly, the cams 41 shift the two-armed levers 38, whereby the fingers 33 are lifted against the tension of the springs 34, immediately before the feeding device 8 starts to advance the top sheet. The top sheet is thereby free to move forward. As shown in the drawings, the fingers I, II, III and IV are actuated by the cams I', II', III' and IV', respectively. As the sheet is moved by the feeding mechanism 8 toward the transporting rollers 12 and 13 and beyond the edge of the shoe 36 of the finger I, its corresponding roller 40 slides down the incline of the cam I', whereby its spring 34 causes the finger to contact with the sheet next to the top sheet, holding thereby this sheet from movement. As the top sheet is advanced further by the feeding means 8, the fingers II, III and IV are one after the other disengaged with their corresponding cams and brought by their respective springs in contact with the sheet next to the top sheet. Attention is called to the fact that the cams are arranged upon the shaft 21 in such a manner, that the finger IV engages the sheet next to the top sheet immediately before the top sheet comes within the reach of the transporting rollers 12 and 13. It will be observed that thus the sheets under the top sheet are held at a plurality of points, maintaining and holding thereby the same in a fixed and proper position and assuring thus practically the separation of but a single sheet of paper. If, however, the sheets are combed, as shown in Fig. 1 of the drawings, each finger will hold one or more sheets under the top sheet in a fixed position, depending upon the relative position of said sheets.

Obviously, it will be necessary to adjust the positions of the cams and the frame 18 upon the machine, as different sizes of paper are placed upon the paper carrying table. For this purpose the key seat 43' in the shaft 21 may be extended throughout the whole length of the shaft 21, or through a portion of the same according to the requirements.

What I claim is:

1. In a feeding machine attachment, the combination with a frame, of a plurality of fingers carried thereby and adapted to engage the pile of paper, means for disengaging said fingers with the pile of paper before the top sheet is being advanced, and means cooperating with said disengaging means for caus-

ing said fingers to engage in succession a plurality of the sheets under the top sheet as the same is being advanced beyond the front edge of each finger.

5. 2. In a feeding machine attachment, the combination with a frame, of a plurality of fingers carried thereby and adapted to engage the pile of paper, means for simultaneously disengaging said fingers with the pile 10 of paper before the top sheet is being advanced, and means coacting with said disengaging means for causing said fingers in succession to engage a plurality of the sheets under the top sheet as the same is being advanced beyond the front edge of each finger.

3. In a feeding machine attachment, the combination with a frame, of a plurality of fingers carried thereby and adapted to engage the pile of paper, a plurality of cams for 20 disengaging said fingers with the pile of paper before the top sheet is being advanced, and means coacting with said cams for causing said fingers in succession to engage the sheets under the top sheet as the top sheet is being advanced beyond the front edge of each finger.

4. In a feeding machine attachment, the combination with a frame, of a plurality of fingers carried thereby and adapted to engage the pile of paper, a plurality of cams for 30 simultaneously disengaging said fingers with the pile of paper before the top sheet is being advanced, and means coacting with said cams for causing said fingers to engage in succession the sheets under the top sheet as the same is being advanced beyond the front edge of each finger.

5. In a feeding machine attachment, the combination with a frame, of a plurality of 40 fingers carried thereby and adapted to engage the pile of paper, a plurality of rotating cams for disengaging said fingers with the pile of paper before the top sheet is being advanced, and means coacting with said cams for causing said fingers to engage in succession the sheets under the top sheet as the same is being advanced beyond the front edge of each finger.

6. In a feeding machine attachment, the combination with a frame, of a plurality of 50 fingers carried thereby and adapted to engage the pile of paper, a plurality of rotating cams for simultaneously disengaging said fingers with the pile of paper before the top sheet is being advanced, and means coacting with said cams for causing said fingers to engage in succession the sheets under the top sheet as the same is being advanced beyond the front edge of each finger.

60 7. In a feeding machine attachment, the combination with a frame, of a plurality of fingers carried thereby and adapted to engage the pile of paper, means for disengaging 65 said fingers with the pile of paper before the top sheet is being advanced, and a plurality

of springs coacting with said disengaging means for causing said fingers to engage in succession a plurality of the sheets under the top sheet as the same is being advanced beyond the front edge of each finger.

8. In a feeding machine attachment, the combination with a frame, of a plurality of fingers carried thereby and adapted to engage the pile of paper, means for simultaneously disengaging said fingers with the pile of 70 paper before the top sheet is being advanced, and a plurality of springs coacting with said disengaging means for causing said fingers to engage in succession a plurality of the sheets under the top sheet as the top sheet is being advanced beyond the front edge of each finger.

9. In a feeding machine attachment, the combination with a frame, of a plurality of fingers carried thereby and adapted to engage the pile of paper, a plurality of cams for 85 disengaging said fingers with the pile of paper before the top sheet is being advanced, and a plurality of springs coacting with said cams for causing said fingers to engage in succession the sheets under the top sheet as the same is being advanced beyond the front edge of each finger.

10. In a feeding machine attachment, the combination with a frame, of a plurality of 95 fingers carried thereby and adapted to engage the pile of paper, a plurality of cams for simultaneously disengaging said fingers with the pile of paper before the top sheet is being advanced, and a plurality of springs coacting 100 with said cams for causing said fingers to engage in succession the sheets under the top sheet as the same is being advanced beyond the front edge of each finger.

11. In a feeding machine attachment, the combination with a frame, of a plurality of 105 fingers carried thereby and adapted to engage the pile of paper, a plurality of rotating cams for disengaging said fingers with the pile of paper before the top sheet is being advanced, and a plurality of springs coacting 110 with said cams for causing said fingers to engage in succession the sheets under the top sheet as the top sheet is being advanced beyond the front edge of each finger.

12. In a feeding machine attachment, the combination with a frame, of a plurality of 115 fingers carried thereby and adapted to engage the pile of paper, a plurality of rotating cams for simultaneously disengaging 120 said fingers with the pile of paper before the top sheet is being advanced, and a plurality of springs coacting with said cams for causing said fingers to engage in succession the sheets under the top sheet as the top sheet 125 is being advanced beyond the front edge of each finger.

13. In a feeding machine attachment, the combination with the sheet advancing means, of a rotary shaft operating in unison 130

motion therewith, a plurality of fingers adapted to engage the pile of paper, means on said rotary shaft for disengaging said fingers with the pile of paper before the top sheet is being advanced, and means coacting with said disengaging means for causing said fingers to engage in succession the sheets under the top sheet as the same is being advanced beyond the front edge of each finger.

10 each finger.

14. In a feeding machine attachment, the combination with the sheet advancing means, of a rotary shaft operating in unison motion therewith, a plurality of fingers
15 adapted to engage the pile of paper, means on said rotary shaft for simultaneously disengaging said fingers with the pile of paper before the top sheet is being advanced, and means coating with said disengaging means
20 for causing said fingers to engage in succession a plurality of the sheets under the top sheet as the same is being advanced beyond the front edge of each finger.

15. In a feeding machine attachment, the
25 combination with the sheet advancing
means, of a rotary shaft operating in unison
motion therewith, a plurality of fingers
adapted to engage the pile of paper, a plu-
30 rality of cams on said rotary shaft for dis-
engaging said fingers with the pile of paper
before the top sheet is being advanced, and
means coacting with said cams for causing
35 said fingers to engage in succession the
sheets under the top sheet as the top sheet
is being advanced beyond the front edge of
each finger.

16. In a feeding machine attachment, the combination with the sheet advancing means, of a rotary shaft operating in unison motion therewith, a plurality of fingers 40 adapted to engage the pile of paper, a plurality of cams on said rotary shaft for simultaneously disengaging said fingers with the pile of paper before the top sheet is being advanced, and means coacting with said 45 cams for causing said fingers to engage in succession the sheets under the top sheet as the same is being advanced beyond the front edge of each finger.

50 17. In a feeding machine attachment, the combination with the sheet advancing means, of a rotary shaft operating in unison motion therewith, a plurality of fingers adapted to engage the pile of paper, means
55 on said rotary shaft for disengaging said fingers with the pile of paper before the top sheet is being advanced, and a plurality of springs coacting with said disengaging means for causing said fingers to engage in
60 succession a plurality of the sheets under the top sheet as the same is being advanced beyond the front edge of each finger.

18. In a feeding machine attachment, the combination with the sheet advancing means, of a rotary shaft operating in unison

motion therewith, a plurality of fingers adapted to engage the pile of paper, means on said rotary shaft for simultaneously disengaging said fingers with the pile of paper before the top sheet is being advanced, and a plurality of springs coacting with said disengaging means for causing said fingers to engage in succession a plurality of the sheets under the top sheet as the same is being advanced beyond the front edge of each finger. 75

19. In a feeding machine attachment, the combination with the sheet advancing means, of a rotary shaft operating in unison motion therewith, a plurality of fingers adapted to engage the pile of paper, a plurality of cams on said rotary shaft for disengaging said fingers with the pile of paper before the top sheet is being advanced, and a plurality of springs coacting with said cams for causing said fingers to engage in succession the sheets under the top sheet as the same is being advanced beyond the front edge of each finger. 15

20. In a feeding machine attachment, the combination with the sheet advancing means, 90 of a rotary shaft operating in unison motion therewith, a plurality of fingers adapted to engage the pile of paper, a plurality of cams on said rotary shaft for simultaneously disengaging said fingers with the pile of paper 95 before the top sheet is being advanced, and a plurality of springs coacting with said cams for causing said fingers to engage in succession the sheets under the top sheet as the same is being advanced beyond the front 100 edge of each finger.

21. In a feeding machine attachment, the combination with the sheet advancing means, of a rotary shaft operating in unison motion therewith, a frame, a plurality of fingers slidably carried thereby, a corresponding plurality of cams on said rotary shaft, means for operatively connecting said fingers with said cams, whereby said fingers are disengaged with the pile of paper before the top sheet is being advanced, and means coacting with said cams for causing said fingers to engage in succession the sheets under the top sheet as the same is being advanced beyond the front edge of each finger. 115

22. In a feeding machine attachment, the combination with the sheet advancing means, of a rotary shaft operating in unison motion therewith, a frame, a plurality of fingers slidably carried thereby, a corresponding plurality of cams on said rotary shaft, means for operatively connecting said fingers with said cams, whereby said fingers are disengaged with the pile of paper before the top sheet is being advanced, and a plurality of springs coacting with said cams for causing said fingers to engage in succession the sheets under the top sheet as the same is being advanced beyond the front edge of each finger. 120 125 130

23. In a feeding machine attachment, the 130

combination with the sheet advancing means, of a rotary shaft operating in unison motion therewith, a frame, a plurality of fingers slidably carried thereby, a corresponding plurality of cams on said rotary shaft, means for operatively connecting said fingers with said cams, whereby said fingers are simultaneously disengaged with the pile of paper before the top sheet is being advanced, and means coacting with said cams for causing said fingers to engage in succession the sheets under the top sheet as the same is being advanced beyond the front edge of each finger.

24. In a feeding machine attachment, the
15 combination with the sheet advancing means,
of a rotary shaft operating in unison motion
therewith, a frame, a plurality of fingers
slidably carried thereby, a corresponding
plurality of cams on said rotary shaft, means
20 for operatively connecting said fingers with
said cams, whereby said fingers are simul-
taneously disengaged with the pile of paper
before the top sheet is being advanced, and
a plurality of springs coacting with said
25 cams for causing said fingers to engage in
succession the sheets under the top sheet as
the same is being advanced beyond the front
edge of each finger.

25. In a feeding machine attachment, the
30 combination with the sheet advancing means,
of a rotary shaft operating in unison motion
therewith, a frame, a plurality of fingers
slidably carried thereby, a corresponding
35 plurality of cams on said rotary shaft, a plu-
rality of levers for operatively connecting
said fingers with said cams, whereby said
fingers are disengaged with the pile of paper
before the top sheet is being advanced, and
means coacting with said cams for causing
40 said fingers to engage in succession the sheets
under the top sheet as the same is being ad-
vanced beyond the front edge of each finger.

26. In a feeding machine attachment, the combination with the sheet advancing means, of a rotary shaft operating in unison motion therewith, a frame, a plurality of fingers slidably carried thereby, a corresponding plurality of cams on said rotary shaft, a plurality of levers for operatively connecting said fingers with said cams, whereby said fingers are disengaged with the pile of paper before the top sheet is being advanced, and a plurality of springs coacting with said cams for causing said fingers to engage in succession the sheets under the top sheet as the same is being advanced beyond the front edge of each finger.

60 27. In a feeding machine attachment, the combination with the sheet advancing means, of a rotary shaft operating in unison motion therewith, a frame, a plurality of fingers slidably carried thereby, a corresponding plurality of cams on said rotary shaft, a plurality of levers for operatively connecting 65 said fingers with said cams, whereby said fin-

gers are simultaneously disengaged with the pile of paper before the top sheet is being advanced, and means coacting with said cams for causing said fingers to engage in succession the sheets under the top sheet as the same is being advanced beyond the front edge of each finger. 76

28. In a feeding machine attachment, the combination with the sheet advancing means, of a rotary shaft operating in unison motion therewith, a frame, a plurality of fingers slidably carried thereby, a corresponding plurality of cams on said rotary shaft, a plurality of levers connecting said fingers with said cams, whereby said fingers are simultaneously disengaged with the pile of paper before the top sheet is being advanced, a plurality of springs coacting with said cams for causing said fingers to engage in succession the sheets under the top sheet as the same is being advanced beyond the front edge of each finger. 75 80 85

29. In a feeding machine attachment, the combination with the sheet advancing means, of a rotary shaft operating in unison motion therewith, a frame, a plurality of fingers slidably carried thereby, a corresponding plurality of cams on said rotary shaft, means for operatively connecting said fingers with said cams, whereby said fingers are disengaged with the pile of paper before the top sheet is being advanced, means coacting with said cams for causing said fingers to engage in succession the sheets under the top sheet as the same is being advanced beyond the front edge of each finger, and means for determining the position of said frame and said fingers relative to the sheet advancing means. 90 160

30. In a feeding machine attachment, the combination with the sheet advancing means, of a rotary shaft operating in unison motion therewith, a frame, a plurality of fingers slidably carried thereby, a corresponding plurality of cams on said rotary shaft, means for operatively connecting said fingers with said cams, whereby said fingers are disengaged with the pile of paper before the top sheet is being advanced, a plurality of springs coacting with said cams for causing said fingers to engage in succession the sheets under the top sheet as the same is being advanced beyond the front edge of each finger, and means for determining the position of said frame and said fingers relative to the sheet advancing means. 101 110 115 120 125 130 135 140 145 150 155 160

31. In a feeding machine attachment, the combination with the sheet advancing means, of a rotary shaft operating in unison motion therewith, a frame, a plurality of fingers slidably carried thereby, a corresponding plurality of cams on said rotary shaft, means for operatively connecting said fingers with said cams, whereby said fingers are simultaneously disengaged with the pile of paper before the top sheet is being advanced, means 130

coacting with said cams for causing said fingers to engage in succession the sheets under the top sheet as the same is being advanced beyond the front edge of each finger, and 5 means for determining the position of said frame and said fingers relative to the sheet advancing means.

32. In a feeding machine attachment, the combination with the sheet advancing means, 10 of a rotary shaft operating in unison motion therewith, a frame, a plurality of fingers slidably carried thereby, a corresponding plurality of cams on said rotary shaft, means for operatively connecting said fingers with said 15 cams, whereby said fingers are simultaneously disengaged with the pile of paper before the top sheet is being advanced, a plurality of springs coacting with said cams for causing said fingers to engage in succession 20 the sheets under the top sheet as the same is being advanced beyond the front edge of each finger, and means for determining the position of said frame and said fingers relative to the sheet advancing means.

33. In a feeding machine attachment, the combination with the sheet advancing means, 25 of a rotary shaft operating in unison motion therewith, a frame, a plurality of fingers slidably carried thereby, a corresponding plurality of cams on said rotary shaft, a plurality of levers for operatively connecting said fingers with said cams, whereby said fingers are disengaged with the pile of paper before the top sheet is being advanced, means 30 coacting with said cams for causing said fingers to engage in succession the sheets under the top sheet as the same is being advanced beyond the front edge of each finger, and means for determining the position of said 35 frame and said fingers relative to the sheet advancing means.

34. In a feeding machine attachment, the combination with the sheet advancing means, 40 of a rotary shaft operating in unison motion therewith, a frame, a plurality of fingers slidably carried thereby, a corresponding plurality of cams on said rotary shaft, a plurality of levers for operatively connecting said fingers with said cams, whereby said 45 fingers are disengaged with the pile of paper be-

fore the top sheet is being advanced, a plurality of springs coacting with said cams for causing said fingers to engage in succession the sheets under the top sheet as the same is being advanced beyond the front edge of each 55 finger, and means for determining the position of said frame and said fingers relative to the sheet advancing means.

35. In a feeding machine attachment, the combination with the sheet advancing means, 60 of a rotary shaft operating in unison motion therewith, a frame, a plurality of fingers slidably carried thereby, a corresponding plurality of cams on said rotary shaft, a plurality of levers for operatively connecting 65 said fingers with said cams, whereby said fingers are simultaneously disengaged with the pile of paper before the top sheet is being advanced, means coacting with said cams for causing said fingers to engage in succession 70 the sheets under the top sheet as the same is being advanced beyond the front edge of each finger, and means for determining the position of said frame and said fingers relative to the sheet advancing means. 75

36. In a feeding machine attachment, the combination with the sheet advancing means, 80 of a rotary shaft operating in unison motion therewith, a frame, a plurality of fingers slidably carried thereby, a corresponding plurality of cams on said rotary shaft, a plurality of levers connecting said fingers with said cams, whereby said fingers are simultaneously disengaged with the pile of paper before the top sheet is being advanced, a plurality 85 of springs coacting with said cams for causing said fingers to engage in succession the sheets under the top sheet as the top sheet is being advanced beyond the front edge of each finger, and means for determining the position of said frame and said fingers relative to the sheet advancing means. 90

Signed at New York, in the county of New York and State of New York, this 20th day of August, A. D. 1908.

JOSEPH KLEIDMANN.
